UNITED STATES PATENT OFFICE.

RONALD F. McFEELY, OF BEVERLY, MASSACHUSETTS, ASSIGNOR TO UNITED SHOE MACHINERY COMPANY, OF PATERSON, NEW JERSEY, A CORPORATION OF NEW JERSEY.

PULLING-OVER MACHINE.

1,162,378.

Specification of Letters Patent. Patented Nov. 30, 1915.

Continuation of application Serial No. 744,184, filed January 25, 1913. This application filed February 24, 1914. Serial No. 820,587.

To all whom it may concern:

Be it known that I, RONALD F. McFEELY, a citizen of the United States, residing at Beverly, in the county of Essex and State 5 of Massachusetts, have invented certain Improvements in Pulling-Over Machines, of which the following description, in connection with the accompanying drawings, is a specification, like reference characters on the 10 drawings indicating like parts in the several figures.

This invention relates to pulling-over machines and has for its object better to pull and draft an upper to its last than has heretofore been done, and this application is a continuation of United States application Ser. No. 744,184, filed January 25, 1913, as to subject-matter that is shown in both applications.

20 Heretofore the last and grippers or the like have been moved relatively in the direction to strain the upper toward the plane of the last bottom and the friction of the upper against the surface of the last has prevented uniform stretching of the upper. 25 By an important feature of this invention the last and the upper are given relative vibratory movements while the upper is being pulled or is under tension whereby to work 30 the last into the upper. This result may be accomplished by a vibratory movement of the grippers or of the last and movement of the last may be effected for this purpose by various means.

35 Herin I have shown this invention as embodied in a pulling-over machine of the type shown in prior United States Letters Patent No. 1,029,387, granted on my application June 11, 1912, and the new movement for 40 working the last into the upper is produced by vibrating the last by force applied thereto through the sole rest. I regard this as the best way to accomplish the desired 45 result in this type of machine but I desire to cover broadly not only the use of a sole rest for vibrating the last to work the last into the upper but also, as generically as the state of the prior patented art will permit, any other means for producing relative vibratory movements of the last and the upper tending to work the last into the upper or to work the upper on to the last better than a steady pull or a thrust will do.

Other features of the invention include means for relating the movements of the sole rest and the heel rest so that the sole rest shall complete a backward movement of the last into the rear part of the upper held by the grippers before the heel rest becomes operative to sustain the last; means for relating a last depressing movement of the sole rest to the operation of the side clamps so that the side clamps shall supplement the upper tensioning action of the grippers at the ball of the last where most difficulty is experienced in getting the upper pulled snugly to the surface of the last; means for depressing the feather edge of the innersole against the last bottom and preventing it from being folded over upon itself during the operation of overlaying the upper into position to be tacked; and means to prevent breakage of the sole rest by collision with side grippers which are set low for use with small uppers.

These and other features of this invention, including certain combinations of parts and details of construction, will now be described in connection with the accompanying drawings and will then be pointed out in the claims.

Figure 1 is a perspective view showing those principal parts of the machine of said prior Patent No. 1,029,387 with which this invention is concerned, this view illustrating the relations of the several parts at the stage of the machine's operation that is also represented in Fig. 2; Fig. 2 is a transverse section in a plane substantially perpendicular to the shoe bottom; Fig. 3 is a perspective view of the sole rest cam; Fig. 4 shows in side elevation many of the parts illustrated in Fig. 1, together with the heel rest controlling means at a stage of the machine's operation earlier than that represented in Fig. 1, the sole rest having drawn the last backward relatively to the grippers but the heel rest not yet having engaged the shoe; Fig. 5 shows a portion of said heel rest controlling means in plan; Fig. 6 shows said parts after the release of the heel rest has occurred; and Fig. 7 is a transverse sectional view substantially on line 7-7 of Fig. 6.

The construction and operation of the illustrative machine, except as herein pointed

out, is the same as that shown and described in said prior Patent No. 1,029,387, and preferably will include the improvements shown and described in my pending application 5 Ser. No. 635,448, and reference is to be had to that patent for the general organization of the machine and for explanation of the parts which it is unnecessary to illustrate or describe in connection with the present improvements, or which are but briefly mentioned herein.

The shaft 2, which carries the rest controlling cams 4 and 5, Fig. 1, also supports cams that give the upper seizing, pulling 15 and overdrawing movements to the toe gripper 6 and the side grippers 8, and appropriate operative movements to the side clamps 10 and to the upper overlaying and fastening means 12 (which latter may be similar 20 to those shown in United States Letters Patent No. 1,007,766, granted Nov. 7, 1911).

The sole rest comprises, as herein shown, feet 3, 3 that engage the innersole on the last bottom near opposite sides of the shoe 25 as in Fig. 2, or that are spaced far enough apart, to enable the rest to effect and control transverse rocking of the last and positioning of the plane of the shoe bottom, as well as with a foot 7 that engages the shoe 30 near the toe. These feet are mounted on a slide 15 that has dove-tailed bearing in a sole rest carrier 16 and is movable lengthwise of the shoe in its carrier by engagement with a pinion 18 by means of rack teeth 35 formed on the upper side of the slide 15 as may be seen in Fig. 1, a spring 17, Figs. 1 and 4, tending to maintain the slide in its advanced position. The pinion 18 is approximately spherical and is fast on the sole 40 rest shaft 20 about the axis of which shaft the sole rest carrier 16 has pivotal movement that is effected in a downward direction by the engagement of the roll 22 on the upper arm of the carrier with a cam face formed 45 on the front end of the cam block 5, the portion of said cam face which is first to act for this purpose after the machine is started being indicated by the reference character 25 in Fig. 3. Return or upward movement 50 of the carrier 16 is effected by a spring 23, Fig. 4, interposed between the lower end or tail of the carrier and a portion of the machine head. By these mountings and devices the sole rest has movements which, 55 broadly, are similar to those described in said prior patent but are differently divided and timed relative to the actuation of other co-operating parts of the machine as will later be stated in detail.

60 The upper arm of the carrier 16 is embraced by a fork 17 pivoted to the frame at 19 the ends of which fork embrace, by runners 24, the cam block 5 at its opposite edges and receive motion from the cam formations 65 26, one group for each runner 24, to move

said upper arm of the sole rest carrier 16 laterally first toward one side and then toward the other, preferably a plurality of times while the grippers hold the upper, and then bring the rest to position with the shoe 70 innersole in a predetermined plane for the operation of overlaying and tacking the pulled upper. One group of cam formations is located back of the other so that neither one will engage the rocker arm associated 75 with the other one. This mechanism produces an automatic transverse rocking or vibration of the sole rest and therefore of the last the bottom of which, or the innersole thereon, is engaged as described by the 80 effect of the sole rest. This vibratory movement of the sole rest is in a direction transverse of the last and takes place about an axis extending substantially parallel with the last bottom from the center of the 85 spherical pinion 18 longitudinally of the last along the slide 15 or its carrier 16, the front portion of which carrier is rounded at its lateral edges to be guided and to turn between faces 28, 28 Figs. 1 and 2, of the 90 machine head. Thus a transverse rocking, vibratory movement of the last within the upper held by the side grippers, and preferably also by the toe gripper, is obtained by which the pulling tension is alternately increased relatively on one side of the shoe 95 and then on the other to obtain more effective stretching of the upper. It may be noted that the described axis is above the shoe bottom so that the last is given a slight 100 bodily lateral vibration. The last is of course free at this time to move as described, being unrestrained by engagement of the side clamps therewith or by such engagement of the heel rest with the shoe as would interfere with the lateral rocking movement of the last. As the illustrated machine is organized the vibration of the last is completed 105 before the heel rest is advanced to its shoe supporting position. It will be obvious that 110 the last may be moved within the upper by other means than by the sole rest, although that is the preferred way of doing it in the present machine, and I desire to obtain for a relative movement of the last and grippers for the purpose described as broad protection as the state of the art will permit.

The sole rest shaft 20, before mentioned, receives motion in the direction to move the sole rest backwardly in opposition to spring 120 17' through a hub 30 that is fast on said shaft and is engaged by a pawl 32 carried by a lever 33 pivoted on the machine head and carrying a roll that is in the path of a cam block 34, Figs. 1 and 4. This cam 125 block is angularly adjustable on an endwise sliding block 35 which bears a roll 36 located in a path in the cam block 4. Through these connections the sole rest slide, the sole rest and the last to which the innersole has been 130

tacked are pulled backward with relation to the grippers to effect foredrawing of the upper, particularly at the sides of the shank and downwardly over the instep incline 5 toward the side grippers 8 which hold the upper at the ends of the tip seam and thus draft the seam ends forwardly. In this way the upper is better pulled over in respect to being drafted in its rear portion and down 10 the instep incline to the lines of the last and backward slant of the tip seam ends is eliminated, which the well-known overdrawing action of the side grippers in a direction obliquely inwardly and backwardly tends to 15 produce. In the machine shown in my said prior Patent No. 1,029,387 I provided a movement of the sole rest for drawing the last backwardly within the upper but in practice this movement of the last so obtained was inadequate because of the interference, as I have now discovered, of the heel rest with the backward movement of the last. I have now modified the heel rest 20 actuating mechanism, as will be described, to eliminate this interference and thereby have succeeded in obtaining the above suggested results most satisfactorily, and protection for this modified organization of the machine is to be obtained herein.

25 The heel rest 40 is supported by rack slides 42, Fig. 6, engaged by pinion sleeves 43 turning loosely on the sole rest shaft 20 and driven by pinions 44 on heel rest shaft 45 which is turned by a rack bar 46 yieldingly mounted in the endwise sliding block 35 above mentioned. These parts as thus far described are herein as they are in said patent but the rack bar 46 is extended, see 30 Figs. 1, 4, 5 and 6, and to it is secured a lateral arm 48 of a plunger 50 that works in a chamber formed in a cylinder 52 fixed on the machine head. A restricted orifice may or may not be provided for governing the intake of air and regulating and delaying the 35 movement of the plunger and of the rack bar 46 and its connections to the heel rest. To control the time at which the advance of the heel rest shall occur the plunger 50 is engaged by a latch 55, Figs. 4 and 5, that is 40 pivoted in the cylinder and is lifted by the engagement of its tail, or an adjustable stop screw 56 therein, by a face on the endwise sliding block 35 at the end of that movement of block 35 during which the sole rest 45 is actuated to draw the last back. Thereafter the plunger allows the heel rest to be advanced to operative position by the spring 47 which surrounds the rack bar 46, and by the use of a restricted air intake orifice, or 50 of a spring 47 which is suitably light, the advance may be made gradual so that no shock tending to displace the shoe shall be produced by the heel rest. A handle 58 attached to the latch permits manual actuation 55 of the latch if desired, the adjustability of the screw 56 permitting it in that case to be set to an inoperative position. These arrangements provide for advancing the heel rest to do its work after the machine may have come to rest to permit inspection of 70 the shoe preparatory to subsequent operations on the shoe, this advance being effected by power stored in the spring 47 while the machine was running and expanded wholly or in part after the power shaft has stopped. 75 As I am advised it is new to provide a device or tool with connections in which power is stored while the machine is running and means for retarding or delaying the transmission of such power and causing the device or tool to act or to come into action after the machine as a whole has come to rest.

80 The side clamps 10 are closed yieldingly as in said prior machine whereby they can adapt themselves automatically to lasts of 85 different widths and shapes and these clamps comprise the last supporters 60 and the friction pads 62 connected by a pinion as appears in Fig. 2. The front face 25 of the sole rest cam has a rise at 63 by which the sole 90 rest and the last are given a downward movement after the side clamps have closed as in Figs. 1 and 2. This forces the last downward to bring the face of the inner-sole level with the top face of the friction 95 pads 62, while the side clamps are frictionally engaging the upper at the sides of the last and the side grippers 8 are still pulling the upper before the tackers move inwardly to wipe the upper over the last bottom. 100 This movement of the last relatively to the friction pads and the last supporters effects a final tightening of the upper in addition to that effected by the gripper pull and this is new as I am advised. The last supporter 105 pads roll outwardly as they are depressed in their outwardly inclined guides and thus tighten the upper to the surface of the last across the top of the last and as they move they turn the pinions that connect them to 110 the friction pads and jam the latter harder against the upper at the sides of the last. The sole rest cam has a further slight rise at 64 which comes into action after the tack insertion to depress the last for the tackers 115 to back off the shoe bottom.

120 A difficulty sometimes occurring in the use of a pulling-over machine upon welt and turn shoes having small uppers and light innersoles or soles having thin or pliable feather edges is that the inner side faces of the side grippers engage and lift the edges of the feather as the grippers pull, and then they fold the feather edge over upon itself as the upper is overdrawn to position for 125 tacking, thus producing a defect in the shoe. I have overcome this difficulty by providing the side grippers with wedge faces 65 formed and arranged on their inner jaws to wedge or crowd the feather edge down upon the last 130

bottom as the grippers move inwardly across the last edge, as illustrated in Fig. 2.

Objectionable interference and some damage has occurred when the machine has been run, as it is customary to do occasionally under some conditions, through its cycle with no shoe in it by collision of the upper overlaying fingers 55', Fig. 2, corresponding to those shown at 55 in said Patent No. 1,007,766, with the side feet 3, 3 of the sole rest. To avoid this interference the sole rest has been improved by pivotally connecting the feet 3 at 66, Fig. 6, and providing a spring 67 to act against their rear ends and hold the feet normally in upraised operative position but permit them to be depressed without breakage when the finger 55' moves inwardly into engagement with them at a time when no shoe is in the machine.

In the operation of the machine a shoe is presented against the feet of the sole rest with the upper between the jaws of the several grippers and the power is applied to turn the cam shaft 2 and cause the grippers to seize the upper and rise for pulling it all as in the machine of said Patent No. 1,029,387. The sole rest is depressed by the portion 25 of its cam block 5 and then is rocked by the edge portions of the cam block to vibrate, wabble or wiggle the last while the grippers are pulling whereby to work the last down into the upper that is being stretched. By this movement of the last the pull on the right side of the shoe, *e. g.*, is increased relatively to the pull on the left side and then on the left side relatively to the right, the alternation being repeated several times. The location of the axis of movement above the last causes the last to be moved slightly from side to side relatively to the upper held by the side grippers and this helps to work the last into the upper. Concentric portions of the edge of cam block 5 come into control of the sole rest before the machine stops so that the cam causes the rest to level the shoe transversely, or position it with both lateral edges at the same elevation, for the operation of the overlaying and fastening mechanisms 12. The latch 55 holds the heel rest away from the shoe as in Fig. 4 while the sole rest draws the last backward to obtain foredrawing of the upper, and this may advantageously occur during the vibratory movement of the last whereby the foredrawing is rendered more effective for working the last backward into the heel part and middle portion of the upper. At the end of the backward movement of the sole rest and the last, and after the vibratory movement of the last, the heel rest is freed by the automatic lifting of the latch by screw 56, or the release of the heel rest may be reserved for the operator to effect by handle 58 after the machine comes to

rest. When the machine is restarted, following the usual examination of the shoe held under tension thereby, the side clamps 10 are closed as in Figs. 1 and 2 and the sole rest is further depressed to bring the shoe to the level at which the overlaying and fastening means 12 can overslide it and to produce the upper tightening and clamping action indicated by the arrows in Fig. 2. This is effected by the second rise in the cam face on the front of cam block 5, which holds the shoe for the tackers to operate after which the side clamps begin to separate and the third rise of cam 5 depresses the shoe slightly farther to permit the tackers to retire without dragging outwardly over the shoe bottom.

Having explained the nature of this invention and described a preferred construction embodying the same, I claim as new and purpose to secure by Letters Patent of the United States as broad protection as the state of the art will permit and I intend that the following claims shall be construed to give effect to this purpose:

1. A pulling-over machine having, in combination, side grippers, a sole rest engaging lateral sides of the shoe bottom, means for relatively operating the sole rest and the grippers to stretch the upper, the sole rest having an arm extending substantially perpendicular to the plane of its shoe bottom engaging face, a cam having on its edge face two cam surfaces one of which is back of the other, and a yoke connected with said sole rest arm and having runners arranged one back of the other on opposite lateral sides of the cam for engagement with said cam surfaces respectively to transmit vibratory motion to the sole rest.

2. A pulling-over machine having, in combination, side grippers, a sole rest engaging lateral sides of the shoe bottom, and means for relatively operating the sole rest and the grippers to stretch the upper, the sole rest having an arm extending substantially perpendicular to the plane of its shoe bottom engaging face into position to be moved to vibrate the last about an axis extending lengthwise of the last.

3. In a pulling-over machine, side grippers, a sole rest, and mechanism for relatively actuating the rest and grippers to pull the upper including means for imparting to the last through the sole rest a movement relative to the grippers about an axis extending lengthwise of the last.

4. In a pulling-over machine, side grippers, a sole rest engaging the shoe bottom near its opposite lateral edges, mechanism for actuating the last and grippers relatively to pull the upper, and means for rocking the rest to cause it to depress first one lateral edge and then the other of the last bottom.

5. In a pulling-over machine, side grippers, a rest for the sole face of a last presented in inverted position to the grippers, means for raising the grippers, and means for 5 rocking the sole rest about an axis extending lengthwise of the last and located above the said sole face to work the last into the upper held by the grippers. 70
6. In a pulling-over machine, side grippers, means for actuating the grippers to pull the upper, resting means engaging the exterior only of the shoe, and means for actuating said resting means arranged to rock the last and relatively to the grippers 10 to cause first one lateral edge of the last and then the other edge to be depressed while the grippers hold the upper. 75
7. In a pulling-over machine, side grippers, a sole rest, mechanism for relatively 20 actuating the sole rest and the grippers to pull the upper, and means to impart to the last during an early portion of the pulling operation laterally rocking motion relatively to the grippers in directions to cause first 25 one lateral edge of the last and then the other edge to be depressed. 80
8. In a pulling-over machine, side grippers, a sole rest, mechanism for relatively actuating the sole rest and the grippers to 30 pull the upper, means to lay the upper over the last bottom in position to be fastened, and means for actuating the sole rest to rock the last to cause first one lateral edge of the last and then the other edge to be depressed 35 and to bring the last to rest with its bottom face in a predetermined transverse plane for the operation of the overlaying means. 90
9. In a pulling-over machine, side grippers to pull an upper over a last, a sole rest 40 and automatically operating means for relatively actuating the grippers and the last to pull the upper with forces which are alternately greater on one side of the shoe than on the other side. 100
10. In a pulling-over machine, side grippers, a sole rest, and mechanism for relatively actuating the sole rest and the grippers to pull the upper having means for effecting an automatic relative movement of 45 the last and grippers in a direction extending laterally of the last. 110
11. In a pulling-over machine, side grippers, a sole rest, mechanism for relatively actuating the sole rest and the grippers to 50 pull the upper, means to lay the upper over the last bottom in position to be fastened, said sole rest being mounted to permit rocking movement in a direction extending laterally of the last, and means for automatically 55 bringing the sole rest into position to locate the shoe bottom in a predetermined transverse plane for the operation of the overlaying means. 120
12. In a pulling-over machine, side grippers, a sole rest and means for relatively 60
- actuating the grippers and the last to pull the upper including means to actuate the sole rest to depress the forepoint of the last relatively to the heel part and also to actuate said sole rest to vibrate the last about an axis extending lengthwise of the shoe. 70
13. In a pulling-over machine, side grippers, a sole rest, mechanism for relatively actuating the sole rest and the grippers to pull the upper, and means to alternately depress one side of the last relatively to the other side a predetermined number of times and then position the two side edges of the last bottom at the same altitude. 75
14. In a pulling-over machine, side grippers, a sole rest, and actuating means for automatically subjecting the upper at the two sides of the last alternately to pulling impulses. 80
15. In a pulling-over machine, side grippers, a sole rest, means for actuating the grippers to pull the upper, and means for actuating the sole rest to vibrate the last laterally with relation to its length between the grippers while the upper is held under tension to work the last into the upper. 85
16. In a pulling-over machine, side grippers, a sole rest, means for actuating the grippers to engage and to pull the upper, and means for depressing the sole rest in a plurality of separate steps while the gripper maintains engagement with the upper. 95
17. In a pulling-over machine, side grippers, a sole rest which is mounted for movement about axes extending longitudinally and transversely of the shoe, and means for actuating it about said axes. 100
18. In a pulling-over machine, side grippers, a sole rest, a block having a cam face on its end, connections therefrom to the rest to move the rest down, a cam face on the edge of the block and connections therefrom for vibrating the rest. 105
19. A pulling-over machine having, in combination, side grippers, a sole rest, and actuating mechanism to cause said rest to depress the last into the upper held by the grippers and then to vibrate the last within the upper. 110
20. A pulling-over machine having, in combination, side grippers, a sole rest and actuating mechanism to cause said rest to depress the last into the upper held by the grippers and then to vibrate the last within the upper and later to depress the last further. 115
21. A pulling-over machine having, in combination, side grippers, a sole rest, actuating mechanism to cause said rest to depress the last into the upper held by the grippers and then to vibrate the last within the upper, and clamps operating to engage the upper on the sides of the shoe after the vibration of the last has been effected, said actuating means having provision for auto- 125
- 65
- 130

- matically depressing the last within the upper engaged by the side clamps.
22. A pulling-over machine having, in combination, side grippers, a sole rest, side clamps, and automatic operating mechanism for said parts arranged to cause the sole rest to depress the last while the upper, at the sides of the shoe is held by the grippers and is frictionally engaged by the side clamps.
23. A pulling-over machine having, in combination, side grippers; a sole rest; side clamps; and automatic operating mechanism for causing the grippers to seize and pull the upper, for causing the side clamps to engage frictionally the upper on the side of the last, and for causing the sole rest to depress the last within the upper frictionally held by the side clamps while the grippers are pulling the upper.
24. A pulling-over machine having, in combination, grippers, means for actuating them to seize and pull an upper, side clamps having friction means for engaging the upper on the sides of the last and last supporters having equalizing connections therewith, and means for depressing the last against said last supporters and between the friction means to cause the latter to wipe the upper upward for supplementing the action of the grippers.
25. A pulling-over machine having, in combination, grippers, means for actuating them to seize and pull an upper, a heel rest, a sole rest, actuating mechanism operating to move the last backwardly into the upper held by the grippers and to advance the heel rest from an inoperative position yieldingly into heel end supporting position, and means to delay the advance of the heel rest until after the backward movement of the last has been completed.
26. A pulling-over machine having, in combination, grippers, means for actuating them to seize and pull an upper, a heel rest, a sole rest, actuating mechanism operatively connected with the sole rest to draw backwardly the last into the upper held by the grippers and acting yieldingly to advance the heel rest into shoe supporting position, a latch to hold the heel rest back, and means arranged to release the latch after the sole rest has substantially completed said movement of the last.
27. A pulling-over machine having, in combination, grippers, means for actuating them to seize and pull an upper, a heel rest, a sole rest, actuating mechanism operatively connected with the sole rest to draw backwardly the last into the upper held by the grippers and acting yieldingly to advance the heel rest into shoe supporting position, and an air check to delay the advance of the heel rest.
28. A pulling-over machine having, in combination, grippers, means for actuating them to seize and pull an upper, a heel rest, a sole rest, actuating mechanism operating to move the last backwardly into the upper held by the grippers, and mechanism timed to advance the heel rest into shoe supporting position after the backward movement of the last has been effected.
29. A pulling-over machine having, in combination, grippers, means for actuating them to seize and pull an upper, side clamps having friction means for engaging the upper on the sides of the last, means to actuate said side clamps resiliently into shoe clamping position, and means for depressing the last into said side clamps to cause said friction means to supplement the action of the grippers.
30. A pulling-over machine having, in combination, grippers, a sole rest, a heel rest, actuating mechanism for relatively actuating the grippers and sole rest to pull an upper about a last and including yielding means which is automatically tensioned to advance the heel rest into shoe supporting position, and a latch to hold the heel rest back.
31. A machine of the class described having, in combination, shoe resting means including a heel rest, automatic mechanism including a yielding element through which power is transmitted to advance the heel rest, and a latch to hold the heel rest from being so advanced.
32. A machine of the class described having, in combination, shoe resting means including a heel rest, automatic mechanism including a yielding element through which power is transmitted to advance the heel rest, a latch to restrain the heel rest from being so advanced while power is stored in said yielding means, and means for automatically releasing the latch to allow the yielding means to act.
33. An automatic shoe machine arranged to perform certain operations on a shoe and then come to rest for other operations to be subsequently performed on the shoe and having, in combination, automatically operating means to work on the shoe, a shoe rest, yielding means through which power is applied while the machine is running to advance the rest from an inoperative position, and means to retard the advance of the rest after the power has been applied and operating to cause the rest to be presented against the shoe after the automatic operation has been completed and preparatory to the subsequent operations for which its support is desired.
34. An automatic shoe machine arranged to perform operations on a shoe and then come to rest for other operations to be subsequently performed on the shoe and having, in combination, automatically actuated de-

5 vices or tools, an additional device or tool to act on the shoe, yielding connections in which power applied while the machine is running is stored to actuate said additional device, and means for retarding the transmission of such power and causing the actuation of the additional tool on the shoe to occur after the machine as a whole has come to rest.

10 35. A pulling-over machine having, in combination, grippers, a sole rest, means for relatively actuating said grippers and rest to updraw the upper, means for relatively actuating the grippers and last to foredraw the upper, and means for relatively vibrating the last and the grippers in a direction substantially perpendicular to the length of the last during the foredrawing movement to work the last into the upper.

15 36. A pulling-over machine having, in combination, grippers, a sole rest, means for relatively actuating said grippers and rest to updraw the upper, means for relatively actuating the grippers and last to foredraw the upper, and means for vibrating the sole rest in a direction transverse to the length of the last and thereby vibrating the last during the foredrawing pull on the upper.

20 37. In a pulling over machine, side grippers, a sole rest, mechanism for relatively actuating the sole rest and the grippers to pull the upper, and means to lay the upper over the last bottom in position to be fastened, said sole rest being mounted to effect 35 a rocking movement of the last in a direction extending transversely across the last.

25 38. A pulling-over machine having, in combination, grippers, means for actuating the grippers to pull the upper and hold it under tension, a shoe rest constructed and arranged to engage the shoe at points spaced laterally apart and located on opposite sides of the longitudinal median line of the last, and operating means by which to move the 40 rest to rock the last about an axis extending lengthwise of the last while the grippers hold the upper.

30 39. In a pulling-over machine, grippers for seizing an upper at opposite sides of the last, means for controlling the position of the last, and mechanism for relatively actuating the grippers and the last to pull the upper and by which the pulling strain is alternately increased on one side and diminished on the other side of the last.

35 40. In a pulling-over machine, side grippers, a sole rest, means for raising the grippers, and means for rocking the sole rest about an axis extending lengthwise of the last to vibrate the last.

40 41. In a pulling-over machine, side grippers, a sole rest and means for relatively actuating the grippers and the last to pull the upper including means for imparting an 45 automatic intermittent quality to the pulling

strain on the upper alternately at opposite sides of the last.

42. A machine for shaping an upper to a last having, in combination, grippers adapted to pull an upper on a last, means for operating said grippers, means for forcing the last into the upper, and means for automatically varying repeatedly the angle of the last bottom relatively to the plane of the end surfaces of the grippers.

43. A machine for shaping an upper to a last having, in combination, means to hold the margin of the forepart of the upper, and power driven means operating automatically to move the last intermittently into the upper during the time the margin of the upper is engaged by the holding means.

44. A machine for shaping an upper to a last having, in combination, means to hold the margin of the forepart of the upper, and power driven means operating automatically to force the last into the upper by a laterally rocking movement while the margin of the forepart is retained by the upper holding means.

45. In a pulling-over machine, side grippers, a sole rest, and operating means for relatively actuating the grippers and the rest to stretch the upper, said grippers being movable over the last bottom to draw the upper over the innersole, and having on their inner sides in position to engage the edge of the innersole inclines arranged to engage the edge of the innersole and wedge it down upon the last bottom as the grippers draw the upper over the innersole.

46. In a pulling-over machine, side grippers, a sole rest, operating means for relatively actuating the grippers and the rest to stretch the upper, said grippers being movable over the last bottom to draw the upper over the innersole, and means for automatically depressing the edge portion of the innersole while the grippers are drawing the upper over the shoe bottom.

47. In a pulling-over machine, side grippers, a sole rest, operating means for relatively actuating the grippers and the rest to stretch the upper, means movable inwardly over the shoe bottom from opposite sides of the shoe to wipe the upper over the innersole, said sole rest having foot portions located in the path of said wiping means, and a support between which and said foot portions there are movable connections to permit the foot portions to be displaced by the wiping means.

48. In a pulling-over machine, side grippers, a sole rest, operating means for relatively actuating the grippers and the rest to stretch the upper, means movable inwardly over the shoe bottom from opposite sides of the shoe to wipe the upper over the innersole, said sole rest having foot portions located in the path of said wiping means, and

a support between which and said foot portions there are pivotal connections permitting the foot portions to be depressed by engagement of the wiping means with them, and means to return the foot portions of the rest to normal position when the wiping means have withdrawn.

In testimony whereof I have signed my name to this specification in the presence of two subscribing witnesses.

RONALD F. McFEELY.
